SECTIONAL HAIR MOLD

Blanche Gabaer, Brooklyn, N. Y.

Application July 5, 1952, Serial No. 297,288

10 Claims. (Cl. 132—38)

1

This invention relates to a hair setting mold having upper and lower sections, the mold being adapted to be placed around the head to embrace the hair and whereby the hair may be combed over the upper section, into a formable lateral opening extending all around the hair mold between the sections, the mold sections having a degree of resiliency tending to maintain the adjacent sections in contacting relation and thereby retain the combed hair in desired wavy form all around the head.

An object of this invention is to provide a hollow, sectional hair mold having upper and lower sections of substantially elliptical form and joined at the inner surface of the sections, each of the sections being independently resilient and compressible, the hair mold having a formable lateral opening between the sections and extending inwardly at, and all around the outer periphery of the sections to permit combed hair to be folded over the top section and inserted into the formable lateral opening and held therein by the resiliency of the sections toward each other to retain the hair between the sections and impart a set wavy form to the hair, whereby after the mold is removed from the set hair, the hair remains in waved form all around the head.

Another object of this invention relates to a sectional or duplex hair setting mold for combing the hair between flexible mold sections which are adapted to embrace the head, for setting the hair of a person having any length of hair, the hair setting mold being also adapted for hair cutting, shaping and permanent waving, and particularly for imparting a desired wavy form to the hair all around the head.

Two coacting tubular and linear mold casings of identical form are used. The material used in one embodiment for filling the mold casings is preferably sponge rubber. The rubber is cut in elongated linear form of rectangular cross-section and after insertion into the linear mold casings, the filled casings are superposed and joined together along the adjacent linear edge to form a sectional hair mold.

The connected hair mold sections are then curved into substantially elliptical shape when applied to the head of the user and this elliptical formation imparts a degree of resiliency to the sections and so that the sections are inherently urged towards each other and thereby enabling the mold sections to engage hair which is combed radially of the mold sections and passed around the upper section and placed in a formable lateral opening formed between the sections with a light pressure from opposite sides to retain the hair in continuous wave form around the head.

2

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a perspective view of the hair mold in operative position on the head of a person.

Figure 2 is a top plan view of the hair mold.

Figure 3 is a cross sectional view of the hair mold, the section being taken on line 3—3 on Figure 2.

Figure 4 is a view, on an enlarged scale, of a fragmentary portion of a fabric casing shown in Figure 3, the casing being formed of two portions which are shown in greatly spaced-apart relation from each other.

Figure 5 is a perspective view of a fragmentary portion of a modified arrangement of the mold sections and an elastic seam therefor.

25 In the illustrated embodiment of the invention, the numeral 10 indicates a hair setting mold in the form of a hollow body having a tubular upper section 11 and a tubular lower section 12. The upper and lower sections 11 and 12 are preferably of identical rectangular cross-section.

30 The upper and lower sections are covered with a flexible fabric 13 which extends around the respective sections, and provides an upright surface 14 common to both sections. The respective edge portions of the fabric 13 after passing around a section are folded at 15 and 16 in parallel relation with the surface 14 defining the interior of the hair mold 10.

35 The folds 15 and 16 are secured together by the stitching 17 to form a seam 18. The seam is arranged so that a small lateral opening 19 may be formed between the sections 11 and 12. This arrangement provides two elongated channels 20, 20, extending along the entire length of the upper and lower sections 11 and 12. The sections 11 and 12 are preferably filled with elongated strips of sponge rubber 21, each strip filling a section in entirety.

40 In use, the elongated sections are curved into substantially elliptical shape when applied to the head of the user and this curvilinear formation tensions the sponge rubber and imparts a degree of resiliency to the sections and so that the sections are inherently urged toward each other and thereby enabling the upper and lower sections to frictionally engage hairs placed between them.

45 50 55 When the user applies the hair mold 10 to the

head, the surface 14 of the hair mold embraces the hair with a pressure due to the tying of cords 22 extending from the respective sections.

The user places the mold around the head with the hair overhanging the mold. The user then combs the hair radially around the upper mold section 11. The hair is then placed in the formable lateral opening 19 between the sections and is engaged by the adjoining faces of the sections with a pressure from opposite sides and so that the end portions of the hairs are retained in tensioned engagement. This forms a continuous hair wave around the head, and this wave remains in substantially permanent form when the hair setting mold 10 is removed from the head.

It is also to be noted that the seam 18 forms a flexible hinge 23 for holding the upper and lower sections 11 and 12 in adjoining unitary relation and for moving the sections to and from each other to provide a formable lateral opening 19 between the sections and an entrance 24 thereto. The flexible hinge 23 extends around the inner surface 14, defining the interior of the hair mold 10. Each of the sections 11 and 12 is preferably filled with inherently extensible compressible elastic material 25.

It is to be noted that the numeral 19 represents a normally closed formable lateral opening between the sections. The operator inserts the hair between the sections by passing through the entrance 24 and by separating the sections at the entrance. The operator places the hair between the sections, the hair extending the entire or partial depth of the sections. The hairs are engaged by the adjoining faces of the sections until such time as a permanent setting is imparted to the hair by the curled form provided by the sections. It is to be noted that I may employ a tie cord between the mold sections to bring the hair into the opening 19 and to retain the hair therein.

It is also to be noted that my hair mold 10 may be used as a hair cutting device to shorten the length of the hair, the operator being able to cut the hair to equal length with a scissors by merely following the outline of the hair mold.

The hair mold 10 may also be used for trimming or shaping the hair by using a blade. The blade is passed over lengthwise of the hair while it lays on the hair mold and this tapers the hair so that a wave form is eventuated.

As best shown in Figures 1 and 4, the hair 26 is placed crosswise of the hair mold 10 and then placed downwardly along the outer upright surface 27 of the upper mold section 11, and is then passed through the entrance 24 and into the formable lateral opening 19 between the mold sections where the hair is frictionally engaged between the adjoining faces of the mold sections.

It is to be noted that when long hair is to be waved, that the hair after inserting in the formable opening 19 is drawn outwardly and downwardly over the lower mold section.

When long hair is to be set in wavy form in my hair mold, I preferably employ a cord 28, which is placed inside the lateral opening 19. The cord 28 is of a length to extend around the body 10 and when its ends are tied, the hair is held firmly between the mold sections. This imparts uniformity to the waved hair and a finish to the overhanging portion of the hair.

In place of the sponge rubber insert, I may inflate the sections of the mold with air or the like.

I may produce an embodiment of the invention identified by the numeral 30 and comprising a

lower mold section 31 and an upper mold section 32 of generally rectangular cross-section. I may employ a heavy elastic cord 33 which is threaded through apertures 34 in stitch-like formation 35 through the curved inner edge portions of the upper and lower mold sections. The elastic cord 33 is tensioned to hold the mold sections in frictional and resilient contacting relation and urges the upper and lower sections toward each other at their inner edges while permitting the outer edges to be spread apart for insertion of the hair therebetween.

The main gist of this invention is to provide a sectional hair setting device designed to cause the hair to be shaped in upwardly waved form and to permanently retain the hair in this form, when the device is removed from the head after use.

In accordance with the patent statutes I have described and illustrated the preferred embodiment of my invention, but it will be understood that various changes and modifications can be made therein without departing from the spirit of the invention as defined by the appended claims.

I claim:

1. A hair-setting mold, comprising a hollow multi-sectional body of substantially elliptical form, the junction of said sections being at the inner surface of said elliptical body, each of said sections being independently filled with resilient and compressible material, means attached to the body for securing the end portions of said sections in unitary relation on the head of a person, said multi-sectional body having a lateral opening extending all around its periphery to permit moistened hair to be folded over the top section into said lateral opening and held therein by the resiliency of said sections toward each other to retain said folded hair for imparting a set wavy form to said moistened hair, whereby after said mold is removed from the set hair, the hair remains in the pre-set and waved form.

2. A mold for setting the hair of a person, comprising a hollow body having upper and lower sections of substantially elliptical form, the junction of said upper and lower sections being at the inner surface of said elliptical body, each of said sections being independently filled with resilient and compressible material, means attached to the body for securing the end portions of said sections in unitary relation on the head of a person, said body having a lateral opening between said sections and extending all around the outer periphery of said sections to permit moistened hair to be folded over the top section into said lateral opening and held therein by the resiliency of said sections toward each other to retain said hair and impart a set wavy form to said moistened hair, whereby after said mold is removed from the set hair, the hair remains in pre-set and waved form.

3. A mold for setting the hair of a person, comprising a hollow body having upper and lower normally linear sections curved into substantially elliptical form, the junction of said upper and lower sections being at the inner surface of said elliptical body, each of said sections being independently filled with resilient and compressible material, means attached to the body for securing the end portions of said sections in unitary relation on the head of a person, said body having a normally closed formable lateral opening between said sections and extending all around the outer periphery of said sections to permit hair to

be folded over the top section and inserted into said formable lateral opening and held therein by the inherent resiliency of said sections toward each other due to the said elliptical curving to retain said hair and impart a set wavy form to said hair, whereby after said mold is removed from the set hair, the hair remains in pre-set and waved form.

4. A mold for setting the hair of a person, comprising a hollow fabric body having upper and lower normally linear sections curved into substantially elliptical form, the junction of the covering fabric of said upper and lower sections being at the inner surface of said elliptical body, each of said sections being filled with resilient material and being thereby independently resilient and compressible, means attached to the body for securing the end portions of said sections in unitary relation on the head of a person, said body having a normally closed formable lateral opening between said sections and extending all around the outer periphery of said sections to permit hair to be folded over the top section and inserted into said formable lateral opening and held therein by the inherent resiliency of said sections toward each other due to the said elliptical curving to retain said hair and impart a set wavy form to said hair, whereby after said mold is removed from the set hair, the hair remains in pre-set and waved form.

5. A duplex mold for setting the hair of a person, comprising a hollow fabric body having upper and lower normally linear sections, each filled with inherently extensible compressible elastic material and curved into substantially elliptical form, the covering fabric of said upper and lower sections being joined at the inner surface of said elliptical body and providing a flexible hinge for moving said sections to and from each other, means attached to the body for securing the end portions of said sections in unitary relation on the head of a person, said body having a normally closed formable lateral opening between said sections and an entrance thereto extending all around the outer periphery of said sections to permit hair to be folded over the upper mold section and inserted into said formable lateral opening and held therein by the inherent resiliency of said sections toward each other due to the said elliptical curving to retain said hair in said folded position and impart a set wavy form to said hair, whereby after said mold is removed from the set hair, the hair remains in pre-set and waved form.

6. A duplex mold for setting the hair of a person, comprising a hollow body having upper and lower sections, each filled with compressible resilient material and curved into substantially elliptical form, said upper and lower sections being joined at the inner surface of said elliptical body and providing a flexible hinge for moving said sections to and from each other, means attached to the body for securing the end portions of said sections in unitary relation on the head of a person, said body having a normally closed lateral opening between said sections and an entrance thereto extending all around the outer periphery of said sections to permit hair to be folded over the upper mold section and inserted into said lateral opening and held therein by the resiliency of said sections toward each other to retain said hair in said folded position and impart a set wavy form to said hair, whereby after said mold is removed from the set hair, the hair remains in pre-set and waved form.

7. A duplex mold for setting the hair of a person, comprising a hollow mould-like body having upper and lower substantially flat, flexible sections adapted to be curved into substantially elliptical form, each of said sections being independently filled with resilient and compressible material, said upper and lower sections being joined at the inner surface of said elliptical body so as to provide a flexible hinge all around the inner surface of said body for urging said sections toward each other, means attached to the body for securing the end portions of said sections to retain said body on the head of a person, said body having a normally closed lateral opening between said sections to permit hair to be folded over the upper mold section and inserted between said sections and held therein by the resiliency of said sections toward each other and impart a wavy form to said hair, whereby after said mold is removed from the set hair, the hair remains in wavy form.

8. A duplex mold for setting the hair of a person, comprising a hollow body having upper and lower sections adapted to be curved into substantially elliptical form, each of said sections being independently filled with resilient and compressible material, said sections being connected at the inner surface of said elliptical body by a circumscribing tie cord, means attached to the body for securing the end portions of said sections, said body being adapted to permit hair to be folded over the upper mold section and inserted between said sections and held therein by said circumscribing tie cord between said mold sections and impart a wavy form to said hair, whereby after said mold is removed from the set hair, the hair remains in wavy form.

9. A mold for setting the hair of a person, comprising a hollow body having a plurality of upper and lower sections curved into substantially elliptical form, each of said sections being independently filled with resilient and compressible material, said sections being flexibly connected at the inner surface of said elliptical body by a circumscribing tie cord in a manner to permit movement of said sections at the outer surface thereof, means attached to the body for securing the end portions of said sections to retain said mold on a head, said body permitting hair to be folded over the upper mold section and inserted between said sections and held therein by said circumscribing tie cord between said mold sections to cause a wavy form to be imparted to said hair by the shape of said sections, whereby after said mold is removed from the set hair, the hair remains in wavy form.

10. A mold for setting the hair of a person, comprising a hollow body having a plurality of upper and lower sections curved into substantially elliptical form, each filled with inherently extensible and compressible means, said sections being elastically connected at the inner surface of said elliptical body while permitting lateral movement of said sections at the outer periphery thereof, means attached to the body for securing the end portions of said sections to retain said mold on a head, said body permitting hair to be folded over the upper mold section and inserted between said sections and held between said sections to cause a wavy form to be imparted to said hair by the shape of said sections, whereby after said mold is removed from the set hair, the hair remains in wavy form.
